United States Patent Office.

D. S. SHANABROOK, OF GREENCASTLE, PENNSYLVANIA.

Letters Patent No. 92,106, dated June 29, 1869.

IMPROVEMENT IN HAND-CARRIAGES.

The Schedule referred to in these Letters Patent and making part of the same.

To all whom it may concern:

Be it known that I, D. S. SHANABROOK, of Green-
castle, in the county of Franklin, and State of Penn-
sylvania, have invented certain new and useful Im-
provements in Hand-Carriages; and I do hereby
declare that the following is a full, clear, and exact
description thereof, reference being had to the accom-
panying drawings, and to the letters of reference
marked thereon, which form a part of this specifica-
tion, and in which—

Figure 1 represents a perspective view, with one
wheel removed;

Figure 2, a plan view; and

Figure 3, a plan view of the machine, inverted.

Similar letters indicate like parts in all the figures.
My invention relates to improvements in hand-car-
riages; and to this end,

It consists in the employment of crank, in combi-
nation with cog-wheels, and such other devices, the pec-
uliarity of which will be hereinafter fully described.

To enable others skilled in the art to which my in-
vention appertains, to make and use the same, I will
now describe its construction and operation.

In the accompanying drawings—

A represents the carriage,

b, the axle-tree, and

B B, the wheels.

The axle-tree, inside the carriage, is made square,
and on the square part are secured the cog-wheels a' b' c'.

On each side of the wheel b', are secured the circular
pieces, formed with projections a' a'.

Over these projections is passed the wire, c', which
is bent around the lever d, said lever being pivoted to
the bottom of the carriage, and is provided with a
spring, working into mortises formed in the end of the
carriage, so that by moving the lever d from one mor-
tise to the other, you change position of the wheel b'
on the shaft, or axle-tree b.

f is a bar, or partition, secured to the bottom of the
carriage, and to which is secured a lever, provided with
a pawl, f', working into the cog-wheel g, secured on
the axle-tree b.

The end of this lever is attached to the foot-lever h,
by the rod h'.

i is a similar lever, provided with a similar pawl,
and working into the cog-wheel i'.

The end of this lever is attached to the foot-lever
h', which is hinged to the carriage.

j j represent two upright bars, which are provided
with the shafts j' j''.

On the shafts j' are secured the cog-wheels H H'
H'', working respectively in the wheels a' b' c'.

The wheel H' is formed with a projection, into
which works the rod p.

This rod is attached to the pivoted lever p', and is
intended to throw the wheel H' in and out of gear with
the wheel b'.

On the shaft j'' are secured two cog-wheels, k k',
which gear with the wheels H H''.

Each of these wheels is provided with the pins k'
k'', the object of which will be hereinafter described.

m represents a metal strap, one end of which is at-
tached to the shaft, or rather to the sliding plate on
which the connecting-wheels n' n'' slide.

This strap is connected with the lever n', which slides
upon a bar, secured to the upper end of the uprights
j j, and by operating this lever, any desired speed may
be given to the carriage.

o o represent wheels, secured to the axle-tree, on
each side of the carriage, and is provided with a spring,
o', and pawl o''.

q represents a seat for the operator, and q', seats for
passengers.

r is a brake, made, as seen in the drawing, for the
purpose of stopping the velocity of the machine.

s is an upright bar, provided, at its upper end, with
the hand-lever s', and at its lower end, inside the car-
riage, with the foot-lever s''.

The upright, s, is provided, outside the carriage,
with the bar, or lever t, the object of which will be
hereinafter described.

t' represents the tongue, made as seen in fig. 3, and
provided, at its front end, with the forward axle-tree t''.

On each end of the axle-tree t'', is pivoted the sec-
ondary axle u, to each end of which is attached a rod,
u', which connects with the lever t, as seen in the
drawing, fig. 3.

By this arrangement, a perfect steering, or guiding-
apparatus is obtained.

Having thus described my invention,

What I claim as new, and desire to secure by Let-
ters Patent, is—

1. The gear-wheels a' b' c', H H' H'', arranged to op-
erate in connection with pinions a' a' n' n'', substan-
tially in the manner and for the purpose described.

2. The slide upon which the wheels n' n'' work, in
combination with the couplers, or projections a' n', and
lever n, arranged to operate as and for the purpose spec-
ified.

3. The combination and arrangement of the gear-
wheels and pinions with levers d and n, slide n', coupl-
ers n', a', and lever p', all operating substantially in
the manner and for the purpose set forth.

4. The combination of foot-levers h h', with rods h'
h'', pawls f' f'', and ratchet-wheels i' g, all arranged to
operate as and for the purpose specified.

5. The wheel o, provided with pawl o'' and spring o',
arranged to operate in connection with wheel B, when
furnished with ratchet-wheels, substantially as de-
scribed.

In testimony that I claim the foregoing as my own,
I affix my signature, in presence of two witnesses.

D. S. SHANABROOK.
